Fig. 5

Fig. 6

FIG. 1 is a side elevation of a suction cleaner showing my new design;

FIG. 2 is a front perspective view thereof;

FIG. 3 is a rear elevation thereof;

FIG. 4 is a side elevation of a modified form thereof showing a polishing brush;

FIG. 5 is a perspective view of the modified form; and,

FIG. 6 is a rear elevation of the modified form.

This application is a continuation of my co-pending applications Ser. Nos. D. 88,215 and D. 88,243, filed Nov. 26, 1965, now abandoned.

I claim:

The ornamental design for a suction cleaner, substantially as shown and described.
